UNITED STATES PATENT OFFICE.

JAMES B. GLASSCOCK, OF WHEELING, WEST VIRGINIA, ASSIGNOR TO F. M. CHURCHMAN AND W. L. TRIPP, OF SAME PLACE.

DESIGN FOR A HAND-RUBBER FRAME.

SPECIFICATION forming part of Design No. 26,468, dated December 29, 1896.

Application filed December 23, 1895. Serial No. 573,155. Term of patent 3½ years.

To all whom it may concern:

Be it known that I, JAMES B. GLASSCOCK, a citizen of the United States, residing at Wheeling, in the county of Ohio and State of West Virginia, have invented a new and original Design for the Frame of a Hand-Rubber for Washboards, of which the following is a specification.

This invention relates to a new and original design for the frame of a hand-rubber for washboards; and it has for its object to provide a design of this character that shall be both useful and ornamental.

The leading feature of the design resides in a frame having a pair of opposite parallel connected side pieces provided with plain straight horizontal lower edges and at opposite sides of their vertical centers with compoundly-curved or sigmoidal top edges merging together at the top of the side pieces and also into the straight lower edges to produce rounded lobes, said compoundly-curved or sigmoidal top edges of the frame side pieces being scalloped by a regular series of convexed semicircular projections, which projections have their adjacent portions meet to form reentrant points.

In the drawings, Figure 1 is a perspective

view of a hand-rubber frame embodying the herein-described design. Fig. 2 is a central 30 longitudinal sectional view.

Referring to the accompanying drawings, 1 1 designate opposite parallel frame side pieces provided with straight plain horizontal lower edges and at opposite sides of their 35 vertical centers with compoundly-curved or sigmoidal top edges producing rounded lobes 2 at the ends and upper sides of said side pieces 1. The compoundly-curved or sigmoidal top edges of the frame pieces are 40 scalloped by a regular series of convexed semicircular projections 3, which projections have their adjacent portions meet to form reentrant points. Cylindrically-shaped figures 4 connect the two side pieces. 45

What I claim is—

The design for the frame of a hand-rubber for washboards herein shown and described.

In testimony that I claim the foregoing as my own I have hereto affixed my signature in 50 the presence of two witnesses.

JAMES B. GLASSCOCK.

Witnesses:

GEORGE I. COOK,
GEO. W. BAYHA.
